composed of flexible cloth material such as heavy canvas or the like. One end of the web 40 is trained around the anchoring shaft 15 and secured to another portion of the web 40 by means of stitching 41.

In operation, the web 40, while secured to one end of the shaft 15, is formed into a loop and trained about the injured limb of the body at a region between the wound and the heart of the victim. The opposite end of the web 40 is inserted through the slot 26 of the spindle 25 and thereafter passes under the roller 16 as indicated in Figure 4. In this position, the slack is taken up by tensioning the free end of the web 40.

After the slack has been taken up, the operating knob 37 is turned to rotate the spindle 25 through the worm 31 in a counterclockwise direction, as viewed in Figure 4. After a half turn of the spindle 25, the web assumes the configuration illustrated in Figure 1 wherein a dual thickness 42 of the web 40 exists between the spindle 25 and the roller 16. In this condition, the web 40 does not slip from the spindle 25 because of the engagement of the opposite faces of the web at the point where the web is in contact with the spindle 25 and at the roller 16. Further rotation of the knob 37 will thereafter cause the loop of the web 40 to be decreased in diameter until a sufficient pressure is exerted on the limb by the web 40 to stop or substantially decrease the flow of blood from the wound.

The tension on the web can be accurately set by careful manipulation of the operating knob 37. As previously explained, the worm drive is irreversible, so that the worm wheel 29 is incapable of rotating the worm 31 and going out of adjustment.

To remove the tourniquet, it is merely necessary to rotate the operating knob 37 in the opposite direction until sufficient slack appears so that the free end of the web 40 may be withdrawn from engagement within the slot 26 of the spindle 25.

From the foregoing it will be appreciated that I have herein provided a compact tourniquet assembly which is capable of being easily operated to supply a predetermined amount of pressure to a tourniquet web. In addition, the particular drive means used in the tourniquet device of the present invention prevents slippage so that accidental release of the tension on the tourniquet web is rendered impossible. The tourniquet can be readily operated by the use of one hand, so that the injured person himself may apply the tourniquet where he has suffered a severe wound on one arm.

It will be understood that modifications and variations may be effected without departing from the scope of the novel concepts of the present invention.

I claim as my invention:

1. A tourniquet device comprising a support member, said support member having an arcuate base surface, a rotatable slotted spindle rotatably mounted on said support member, anchoring

means carried by said support member above said base surface, a flexible web having one end secured to said anchoring means, said web being sufficiently long to extend below said base sur-

face and form a loop below said base surface, said web having a portion passing through the slot in said spindle, a roller carried by said support member above said base surface for guiding a portion of said web beyond that portion passing through said slot, and an irreversible worm drive means operatively connected to said spindle for adjusting the length of web included between said anchoring means and said roller.

2. A tourniquet device comprising a support member, said support member having an arcuate base surface adapted to engage a limb, a rotatable slotted spindle rotatably mounted on said support member, anchoring means carried by said support member above said base surface, a flexible web having one end secured to said anchoring means, said web being sufficiently long to extend below said base surface and form a loop below said base surface, said web having a portion passing through the slot in said spindle, a roller carried by said support member above said base surface for guiding a portion of said web beyond that portion passing through said slot, said web being reversed in direction in passing through said slot to provide a dual thickness of web between said spindle and said roller, and an irreversible worm drive means operatively connected to said spindle for adjusting the length of web included between said anchoring means and said roller.

3. A tourniquet device comprising a support member, said support member having an arcuate base surface adapted to engage a limb, a rotatable slotted spindle rotatably mounted on said support member, anchoring means carried by said support member above said base surface, a flexible web having one end secured to said anchoring means, said web being sufficiently long to extend below said base surface and form a loop below said base surface, said web having a portion passing through the slot in said spindle, a roller carried by said support member above said base surface for guiding a portion of said web beyond that portion passing through said slot, a worm wheel carried by said spindle, and a worm operatively engaging said worm wheel, the pitch on said worm wheel being insufficient to drive said worm whereby the effective dimensions of said loop are changed by rotation of said worm.
